ARRANGEMENT IN DIRECTED RADIO BEACONS

Frans Joel Fransson, Lidingo, Sweden, assignor to Svenska Aktiebolaget Gasaccumulator, Lidingo, Sweden, a corporation of Sweden

Application November 8, 1955, Serial No. 545,665

Claims priority, application Sweden December 6, 1954

7 Claims. (Cl. 343—107)

Directed radio beacons have been more and more used as approaching beacons. Among such directed radio beacons is included the so-called course indicating beacons, which function in such a way that one listening to the signal from the course indicating radio beacon by means of an open antenna and a usual radio receiver which, disregarding the wave-length, may be a normal broadcast receiver. This radio beacon, has the purpose of indicating a given course with a high degree of precision, said course being followed when approaching a harbour through a narrow channel past an amount of subwater rocks or the like, and the beacon is made in such a way that when deviating from the stated course in one direction, one will hear a signal characteristic for this direction, and when deviating in the other direction, one will hear another signal. These signals are preferably composed by two Morse signs, complementing each other as for instance the Morse letters a and n or e and t. When one is in the indicated course, one will thus hear both of the Morse signs with the same intensity, and as these are complementing each other, they are not heard separately but together in a continuous tone.

Previously a radio transmitter was combined with two antenna systems, one of which had a direction characteristic like the figure 8, whereas the other one had a circular direction characteristic. The composed direction characteristic then acquired a form which should theoretically be exactly a cardioidic curve, if the two direction characteristics had the same maximum signal intensity. As a matter of fact the characteristic deviates a little from this exact form. In modern systems of this kind the idea of providing one antenna system as an open antenna with a circular characteristic has been abandoned, and in many a case the directed antenna system has not been provided as a frame antenna, i.e. in such a form that the most pointed out direction diagram similar to the figure 8 will be obtained, the obtained direction characteristic is indicated as cardioidic even though this is a little misleading. In the following the indication of cardioidic direction characteristic will be used in the last-mentioned, broader meaning.

By changing the phase direction of the voltage with which one of the antenna systems is fed, one will then note that the cardioidic direction characteristic swings to and fro around an unsymmetrical axis, which causes the signal intensity in a given direction alternatively to be stronger and weaker. The change in phase direction takes place in time with the given complementary code. Only in the direction, marking the level for the swinging axis of the direction characteristic, one will obtain a constant signal intensity, and this level is then used as course indicating level, by the antenna system being mounted in such a direction, that this level coincides with the course which should be indicated.

A very common form of such course indicating, directed radio beacons is using two usual frame antennas, placed in the same place in mutually perpendicular di-

2

rections. One frame antenna will then transmit its field in the marked course direction, whereas the other frame antenna transmits its field in a level perpendicular thereto. The invention will for the sake of simplicity be described below in connection with a system, containing such antenna systems, but it is understood that the invention is not therefore limited to the use only in connection with such antenna systems, and also that the obtained characteristic, although below mentioned as a cardioidic characteristic, may rather considerably deviate from the mathematical cardioidic curve.

Common to all kinds of such directed radio beacons as mentioned above is that the course indication may be made very sharp, but also that the demand for sharpness in the course indication is only gained at the cost of a decrease of the signal intensity of the antenna systems and consequently also of the range of the beacon. However, cases may occur when it is of a very great importance to obtain both high direction sharpness and great range. This is for instance the case when the beacon is used as an approaching beacon of a harbour, which is placed at the bottom of a deep bay or other navigable channel, within which one requires a high sharpness of direction, but otherwise is facing open water, so that it is of importance that one should already at a great distance from the radio beacon get contact with it. In such cases, however, there is considerably less demand for a high sharpness.

The present invention relates to an arrangement in directed radio beacons of the common kind now mentioned, by which the demand for high sharpness of course indication close at hand is met and there is also provided great range with a decreased sharpness.

The invention will be described below in connection with a chosen form of execution, shown on the attached drawings, in which Fig. 1 gives an example of topographical circumstances where a directed radio beacon of the present kind may be of value, Fig. 2 and Fig. 3 indicating two different examples of direction diagrams. Fig. 4 shows a principal wiring diagram of a radio beacon according to the invention, and Fig. 5 shows a diagram of elements of the wiring system.

In Fig. 1 it is assumed that the beacon is placed as an approaching beacon of the city Town, which is situated at the bottom of the deep and narrow Bay, which extends inwards from the open water Sea. It is further assumed that the Bay has substantially an eastward direction and that the subwater rock in this Bay is of such a kind that it is necessary to keep a very exactly determined course when approaching the city Town. The coast on each side of the mouth of the Bay is, however, such that the sailing onto the coast may take place from any deliberate direction within an angle which passes from north course past westerly course to southerly course. It is thus desirable that outside the mouth of Bay the same directed radio beacon shall be used as an approaching beacon towards the coast line, but there, obviously, the sharpness of course indication must be essentially less. This has been indicated in Fig. 1 by means of the angles β and γ , limited by dash-dot lines, the angle β indicating the sharpness of course indication when sailing in Bay, whereas the angle γ indicates the sharpness of course indication when approaching the coast of Sea.

If one now provides the directed radio beacon with two frame antennas 10 and 11, see Fig. 2, then one of said antennas 11 should be directed in such a way that its field diagram similar to the figure 8 will have its longitudinal symmetrical axis in the mean line of the course 70 12, whereas the other frame antenna 11 is directed in such a way that its direction diagram with its longitudinal symmetry axis falls perpendicularly to the course line

12. The first mentioned diagram is indicated 13 and the latter one 14. It is now assumed that both of the frame antennas are fed from the same generator, and that they are mutually alike, so that the two direction characteristics are symmetrical, although displaced by 90° in the horizontal plane. In this case the precision of the arrangement will be very low. The sharpness of course indication may be indicated as the angle between the direction of the course and the direction, indicating equally strong field intensities from both direction diagrams. If this angle of sharpness is indicated α_0 , then it will obviously be 45° in the example, shown in Fig. 2, or in other words $\tan \alpha_0 = 1$. As a matter of fact, for the angle α_0 the tangent of the angle is equal to the field intensity of the direction of the course, divided by the field intensity across said course direction.

For a deliberate angle α therefore the field intensity in the direction α is equal to $F_2 = f_a \cos \alpha + f_b \sin \alpha$, when the current in one antenna system is in counterphase to the current of the other antenna system, and

$$F_2 = f_a \cos \alpha - f_b \sin \alpha$$

when the current in both of the antenna systems is in phase. In these equations f_a indicates the field intensity in the direction 12 from the antenna 11 and f_b indicates the field intensity across the direction 12 from the antenna 10. The course width, or in other words the angle β or γ , within which the two signs may practically be understood by the human ear as equally strong, and where one thus can no longer apprehend any difference in sound intensity and consequently also not separate the signs from each other, is dependent upon the magnitude of the angle α_0 . From practical experience one knows of course that the relation between the width of the course and the angle α_0 is different for different listeners, but it is assumed that this relation may with good approximation for practical needs be put to 10%, which would in other words mean that in the case, shown in Fig. 2, the width of the course should be 4.5°. It is assumed that this course width is too big for approaching in the Bay.

It is now possible to decrease the value of the course width or, in other words, of the angle α_0 by decreasing the field intensity f_a in the direction of the course, as evident from Fig. 3. The direction diagram 14 from the frame antenna 10 is there the same as in Fig. 2, but the field intensity in the course direction has been decreased, so that the direction diagram 13 is replaced by a much weaker direction diagram 13'. It is also evident that the angle α_0 has been decreased to the value α'_0 . The course angle has of course thereby decreased proportionally, but it is regrettable that also the signal intensity in the course direction has decreased proportionally to the decreased field intensity. Thereby the range of the beacon has been limited in such a way, that it may be assumed that it may only be well heard up to the distance circle 15, see Fig. 1, whereas it had been desirable to be able to hear the indication up to the distance circle 16. Within the field between the two distance circles 15 and 16, however, the course angle need not at all be small, and it may even be of advantage to the navigator that the course angle be wider. It is true that one could increase the range of the radio beacon in such a way that it may be well heard up to the distance circle 16, but this would mean that the system would be more expensive and it would mean an increase of the risk for reflections of the radiation to be of such an intensity to be heard separately. It must be kept in mind that for the radio beacons now in question substantially short and ultra-short wave-lengths are used, and these are especially adapted for forming of reflections. Further the advantage of the wider course angle at greater distances from the coast line would be lost.

Here the invention sets in: The feeder conduit to the

antenna, which is active in the course direction, i.e. the antenna 11, may be switched in such a way that one alternatively feeds a higher amount of power and a smaller amount of power to this antenna, and during each of the periods for higher or smaller power, respectively, a signal is transmitted during repeated reversals of phase of one antenna, for instance also the antenna 11.

An arrangement for execution of this function is schematically shown in Fig. 4. An oscillator or transmitter 10 is there indicated by 17. This oscillator or transmitter is by means of the conduits 18 connected to the antenna 10. A branch conduit 19 leads to the phase reverser 20, which is schematically indicated in the form of a two-pole switch. This would not need any further description, because it is known per se to the man, skilled in the art, in many different forms. The output conduits 21 from the phase reverser 20 lead to the second antenna 11. The phase reverser 20 is suitably controlled by electromagnetic means from a pulse transmitter 22. This is schematically indicated by means of the conduits 23 from the pulse transmitter to a relay winding 24, the armature 25 of which is assumed to control the contacts of the phase reverser 20.

In the parts hitherto described the arrangement according to Fig. 4 is known. The new items according to this invention constitute a filter device connected into the conduit 18 and/or 19 with the function that when the filter is connected into this conduit, the signal intensity from the antenna 11 is heavily reduced, and when the filter is disconnected, the same signal intensity is again increased to its initial value. It is assumed that the filter contains the inductance coil 26—27, one part 26 of which is continuously connected in the conduit 19 to the antenna 11, whereas the other part 27 can periodically be bypassed or connected into the conduit by means of a contact 28, subordinated under a relay 29, said relay being by means of the conduits 30 connected to the code transmitter 22. It is without any decisive importance to this invention, how the tuning of the transmitter 17 takes place, but for the sake of simplicity it is assumed that this tuning takes place by means including a condenser 31. It is now obvious that the circuit will be disaligned, when the inductance 27 is connected into it. For resetting the alignment to its correct value a further condenser 32 is therefore provided to be connected in parallel to the condenser 31 by means of a contact 33, which is also controlled by the relay 29.

It is assumed that in the radio beacon now shown the transmitter is audio frequency modulated. The modulator is in a way known per se built into the transmitter 17. As this is well known to every man skilled in this art, no further description would be necessary. However, the transmitter contains an audio frequency generator, which pulses at a given grid bias voltage, and for the signal modulation of the transmitter a conduit 34 is therefore provided from the code transmitter to the proper transmitter for alternatively connecting and disconnecting the required grid bias voltage from the audio frequency generator, so that a modulation will take place in the transmitter with a code of Morse signs or the like, determined by the code transmitter.

The code transmitter 22 thus has three different functions to fulfill: It should control the phase reversal by means of the conduit 23 and the relay 24, it should further control the switching for higher or smaller course width, respectively, by means of the conduit 30 and the relay 29, and it should finally control the order of the codes in the transmitter by means of the conduit 34. There are different ways of constructing a code transmitter, which is capable of executing these three functions, and while such an arrangement is described below, consisting in three motor-driven contact discs, this is only to be regarded as one chosen arrangement for the purpose, which is especially suitable in cheaper and more simple

systems, but the invention is not limited to this arrangement.

The three contact discs are indicated 35, 36 and 37. It is assumed that they are driven around by means of a motor 38 with such a speed that a full turn is described for instance in two minutes. Each of the contact discs is in connection with the grounded pole of a source of voltage 39. In their circumferences conducting segments are introduced, which are shown in black in the drawing, whereas the segments indicated by white are assumed to be insulating. It is assumed that the contact discs rotate in the direction of the arrows 43, when the system is operating.

Under these provisions the system will function in the following way:

When the part of the contact disc 35, at the arrow point 43, said part of the contact disc being insulating, gets under the brush 40, then the connection of the voltage to the relay 29 is cut off, said relay having been energized during half a turn of the contact discs, but now being de-energized. The inductance coil 27 is thereby connected into the circuit of the antenna 11, and this antenna will consequently radiate with decreased intensity, which causes in the above indicated manner an increase of the sharpness of course indication and a decrease of the course angle, respectively. Simultaneously the earlier connected condenser 32 is switched out, and the system functions with high sharpness for transmitting the signal, intended for guiding the vessels into the narrow Bay, but it has a range which is decreased to a corresponding degree.

At the same moment the circuit through the conduit 23 to the relay 24 is opened as the brush 41 is on a segment of the insulating material on the contact ring 36. During this time, however, the contact brush 42 will contact the conductive segment on the circumference of the contact ring 37 three times, and three modulation pulses will be transferred to the transmitter, so that the signal transmitted will correspond to the Morse code of the letter O, which is three moderately long dashes. During the open interval before the following equally long contact piece on the circumference of the contact ring 37, the brush 41 will, however, contact the conductive segment on the contact ring 36, and by means of the conduit 23 feed current to the relay 24, which causes a phase reversal of the signal from the antenna 11. During the time, when the phase direction of the signal from the antenna 11 is in this way reversed, only one pulse is transmitted from the contact disc 37. It is therefore evident that when this procedure is repeated during the upper half turn of the contact discs as shown in the drawing, the signal containing three dashes (the letter O) will be heard stronger on one side of the correct course into the Bay, whereas the signal, containing one dash (the letter T) will be heard stronger on the other side of the correct course. This change of signals takes place with a high degree of sharpness, and consequently one will on board the vessel, which is exactly in the course direction, continuously hear equally long and equally strong signals, repeated at equal intervals. If the vessel should, however, get out of course, then either each fourth pulse will be heard stronger than the remaining pulses or weaker than the remaining pulses, and the helmsman will then know, in which direction he has to turn in order to position the vessel on the correct course.

One minute or, in other words, the time of half a turn of the contact discs having run in this way, the contact brush 40 will contact the conductive segment on the contact disc 35. The relay 29 is thereby energized, and it will remain energized during the next half turn of the contact discs, which with the assumed speed of rotation will correspond to one minute. By means of the relay contact 28, the inductance coil 27 is then bypassed, and the signal intensity from the antenna 10 is consequently increased. Simultaneously the condenser 32 is

again connected into the circuit for restoring the tuning, now destroyed. After the lapse of five seconds, corresponding to 15° on the periphery of the contact disc, the contact brush 41 will contact a conductive segment on the contact ring 36, and current is now closed through the conductor 23 to the relay 24, which is attracted and will provide a switching off of the phase reverser of the antenna 10. Immediately thereafter the contact is closed between the contact disc 37 and the brush 42, three times at short intervals, so that the code sign for the Morse letter S (three dots) is transferred to the transmitter 17 and transmitted through both of the antenna systems. Thereafter the contacting at the contact disc 36 ceases, and the relay 24 returns to its position of rest, the phase direction consequently being reversed on the current, fed to the antenna 10, and thereafter, by means of the contact disc 37 and the contact brush 42, the Morse sign for N (one long and one short pulse) is transmitted. This procedure is thereafter continued during the remainder of the turn of the contact discs, until the initial points again contact the contact brushes, all of the above described procedure being thereafter repeated.

It will, however, be evident from the above that during the second minute, corresponding to the half circular periphery part of the discs, turned downwards in the figure, the Morse codes S and N will alternatively be transmitted, at the same time as the antenna 11 is reversed each time, so that one of the Morse codes will be heard stronger on one side of the course, whereas the other Morse code will be heard stronger on the other side of the course. Choosing now the phase positions of the antenna 11 correctly, it will be noted that the Morse code N will be heard stronger on a vessel, which is accidentally deviating northwards from the course, whereas the Morse code S will be heard stronger on board a vessel, which is deviating southwards from the course. During all of this part of the function of the beacon the antenna 11 is, however, fed with strong current, the range is wide, so that the signals may be received far away in open water, and the sharpness of course indication is not unnecessarily great. The beacon will, in other words, in periods, which may for instance last each one minute, alternatively transmit according to a first system and according to a second system. During the transmission according to the first system the beacon has high sharpness of course indication and small range. The high sharpness of course indication requires, in order to be used completely, a transmission according to the complementary code principle. This principle does not necessarily mean that the two codes complementing each other should fill out the time fully, so that a continuous tone is obtained, but they may also be regarded as complementing each other, if one obtained a regularly repeated code of constant signal intensity, as will be the case, when the Morse codes of the letters O and T are combined into a continuously repeated series of equally long dashes, interrupted by equal intervals. During the transmission according to the other system, the beacon has high range but less sharpness of course indication, but it can be used across a rather wide approaching angle. Here the code is different, so that confusion will not result. This code giving can of course also be made in such a way that it is a complementary code, but this is not at all necessary. The complementary code is of importance only in such cases when one requires a high sharpness of course indication, but this is not the case, when transmitting according to the second system. The codes of the letters N and S also differ essentially from the codes of the letters O and T, and confusion may scarcely be assumed to appear, but they do not form mutually complementary codes.

The codes of the transmission according to the second system may suitably be chosen in such a way that they form simultaneously the identification signal of the directed radio beacon.

When navigating according to the above description,

it is, however, not at all suitable that the navigator exclusively listens to the transmission of one system, when he is far away at sea, or according to the other system, respectively, as soon as he can hear the signals reliably. On the contrary, cases may appear, when it is of great importance for the security of navigation that the navigator listen to both of the transmissions.

For instance cases may appear, when one has chosen the signal intensity of the antenna 11 during the transmission with high sharpness of course indication in such a way that the above mentioned angle, indicated by α_0 , is equal to 4° . The tangent value of 4° is about 0.07, and the relation between the signal intensity during one code and during the other code will therefore in this case be for $\alpha=1^\circ$.

$$\frac{F_1}{F_2} = \frac{f_a \cdot \cos \alpha + f_b \cdot \sin \alpha}{f_a \cdot \cos \alpha - f_b \cdot \sin \alpha} = \frac{0.07 \cdot \cos \alpha + \sin \alpha}{0.07 \cdot \cos \alpha - \sin \alpha}$$

This equation will also be satisfied for a value of α about 16° . Assuming now that a vessel is approaching the mouth of the Bay with a course error of 16° , then one can on board said vessel, by exclusively listening to the transmission with high sharpness of course indication, can be brought to the miscomprehension that the vessel is only 1° out of course, and one may then steer into dangerous waters with a catastrophe as a consequence. However, if one listens to the transmission with high sharpness of indication then this miscomprehension may be avoided. The risk of such mistakes has prevented in older systems increasing the sharpness of course indication. In a system according to the invention, however, by using both systems of transmission this disadvantage is overcome.

The invention is of course not limited to the form of execution thereof, described above and shown in the drawings, but different modifications of the invention may be made within its frame. It is for instance not necessary that the antenna 11, which has the sharp signal intensity in the direction of the course, the so-called course antenna, should also be switched between higher and lower signal intensity, but in certain cases, dependent upon the geographical and/or nautical circumstances it may be desirable instead to switch the other one or the cross course antenna between a higher and a lower signal intensity.

What is claimed is:

1. A directed radio beacon comprising, in combination, a transmitter, a pair of frame antennas, means connecting said transmitter to said antennas whereby said antennas transmit a predetermined code, one of said antennas having a strong field intensity in a selected direction, the other of said antennas having a strong field intensity in a direction perpendicular to the selected direction, means including a filter device for periodically switching the transmission of one of said antennas between high and low signal intensities.
2. A radio beacon according to claim 1 and further including means for periodically reversing the phase of the transmission of one of said antennas.
3. A radio beacon according to claim 1 and further including a code transmitter connected to said transmitter for determining the code to be transmitted.
4. A radio beacon comprising, a pair of frame antennas, an oscillator connected to said antennas, a code transmitter connected to said oscillator for determining the code to be transmitted, one of said antennas having a strong field in one direction and the other of said antennas having a strong field in a direction angularly disposed thereto, means for periodically switching the transmission of one of said antennas between high and low signal intensities.
5. A radio beacon according to claim 4 and further including means for periodically reversing the phase of the transmission of one of said antennas, said transmission switching means, said phase reversing means, and said code transmitter being operable by a common drive means.
6. A radio beacon according to claim 4, said code transmitter including means for differentiating the code between periods of high signal intensity and periods of low signal intensity.
7. A radio beacon according to claim 4, said last-named means including an inductance coil and means for bypassing the inductance coil.
